(57) **CLAIM**

(22) Filed: **Jan. 29, 2004**

The ornamental design for a tread portion of an automobile tire, as shown and described.

(30) **Foreign Application Priority Data**

Jul. 31, 2003 (JP) 2003-022285

DESCRIPTION

(51) LOC (7) Cl. **12-15**

FIG. 1 is a perspective view of top, front and one side of the tread portion of an automobile tire showing my new design, it being understood that the tread pattern repeats uniformly throughout the circumference of the tire;

(52) U.S. Cl. **D12/579**; D12/602

FIG. 2 is a front elevational view thereof, the top and bottom plan views being identical thereto;

(58) Field of Search D12/551, 552,

FIG. 3 is a rear elevational view thereof;

D12/553, 574, 579, 580, 586, 587, 588,

FIG. 4 is a right side elevational view thereof;

594, 595, 598, 600, 601; 152/209.1, 209.9,

FIG. 5 is a left side elevational view thereof;

209.13, 209.25, 209.28

FIG. 6 is an enlarged fragmentary front elevational view thereof; and,

(56) **References Cited**

FIG. 7 is a cross-sectional view thereof taken along the line 7-7 as shown in FIG. 6.
